UNITED STATES PATENT OFFICE.

WILLIAM CAMERON, OF CHICAGO, ILLINOIS, ASSIGNOR TO CAMERON CAN MACHINERY COMPANY, OF CHICAGO, ILLINOIS, A CORPORATION OF ILLINOIS.

CAN-BODY-FORMING MACHINE.

Application filed October 14, 1925. Serial No. 62,425.

This invention relates generally to machines for forming can bodies and pertains more particularly to a mechanism for necking in said bodies.

5 Those can bodies which are designed to receive a removable slip cover at one end are preferably necked in or reduced in diameter at the end which receives the cover substantially the thickness of the tin plate from 10 which the body and cover are formed, so that the flange of the cover will lie flush with the exterior surface of the body thereby presenting a smooth surface for the reception of a label or other paper covering which customarily surrounds the can.

It has heretofore been customary to perform the necking in operation by means of internal expanding dies cooperating with external contracting dies which together reduce 20 the diameter of one end of the can, or in other words, accomplish the necking in.

Prior to my invention the use of internal expanding dies has been considered essential for two reasons; first, because it was customary to neck in the rear rather than the forward end of the body and it was necessary to reduce the size of the internal die after the necking in operation, in order that the necked in end of reduced diameter might be slid over 30 the die and discharged, and second; because it was not considered possible to do a smooth necking in job and produce an uncrinkled necked in body unless the necking in operation were started with the inner die in contact 35 with the inner perimeter of the body whereby the metal of the body would be held between the internal and external dies and prevented from crinkling while the necking in operation was being performed.

40 I have discovered, however, that the necking in operation can be satisfactorily performed on a solid non-expansible mandrel which is not only much cheaper to manufacture but is also more durable in use and furthermore, by my invention, the necking in can 45 be performed not only satisfactorily but in a very superior manner.

Other objects and many advantages of my invention should be readily appreciated, as 50 the same becomes better understood, by reference to the following description when considered in connection with the accompanying drawing.

Referring to the drawings:

55 Fig. 1 is an end elevation, with a portion of

the housing broken away to show the underlying parts, of a necking in mechanism embodying my invention.

Fig. 2 is a sectional view on the line 2—2 of Fig. 1 and

60 Fig. 3 is an enlarged vertical sectional view through the mandrel and a portion of the dies and also showing feeding mechanism.

Referring to the drawings more in detail, reference character 5 indicates a base adapted 65 to be mounted upon a bracket at the rear end of a can body forming machine and upon the base is supported a housing 6 within which the external necking in dies are mounted. A portion of the horn 10 which extends longitudinally of the can body forming machine and upon which the can bodies are formed, is shown in Figs. 2 and 3 and to the rear or delivery end of this horn is attached my novel necking in mandrel, the details of which will 70 be later described.

75 The housing 6 which is disposed in alignment with the necking in die is provided internally with a plurality of radially disposed webs 7 forming a series of guide-ways, preferably four in number, in each of which a die carrier 8 is adapted to reciprocate. Each die carrier 8 is equipped at its inner end with a die 9 secured to the carrier by a bolt 11, the inner or operable portions of the dies being 80 shaped to conform to the contour of the necking in mandrel as will be apparent from Fig. 3.

85 Each die is normally urged outwardly away from the mandrel by a spring 12 and is forced inwardly into cooperative relation with the mandrel by a roller 13 mounted upon an oscillatory ring 14 which is oscillated in the usual manner through a reciprocatory link 15 to move the rollers along the cam surfaces 16 formed at the outer end of each die carrier so that all the dies are forced inwardly simultaneously to snugly embrace and contract a can body 17 around the mandrel. Each spring 12 is compressed between the 90 end of a slot formed in its die carrier and a stud 18 projecting inwardly from the front wall of the casing 6.

95 The necking in mandrel, instead of being expansible as has heretofore been customary, is solid in construction and while it may be made in one piece, I prefer, in order that it may be adapted for making necks of various lengths, to make it in a plurality of pieces. For instance, as shown in Figs. 2 and 100 110

3, it comprises an inner piece or plate 19 of substantially the same dimensions as the interior of the can to be necked in, a center piece 21 smaller in cross sectional area than the piece 19 by substantially the area of the thickness of the tin plate of which the can body is formed, and an outer or end plate 22 of still smaller diameter, the three pieces being rigidly secured to the end of the horn 10 by bolts 10 23.

A can body is fed along the horn to the necking in station by any suitable feed mechanism and, when properly positioned, the dies 9 are forced inwardly with sufficient power to 15 displace the metal of the can body inwardly from its original plane, a distance substantially equal to the thickness of the tin plate to thereby form the inwardly offset neck 24. The cooperative action of the solid mandrel 20 and the inwardly moving dies is such that the neck is formed smoothly and without the production of wrinkles in the tin and since the mandrel is of solid construction, it may be economically manufactured and its 25 durability is almost unlimited. Longer or shorter necks may be produced by substituting a thicker or thinner plate for the plate 21 shown in the drawings. It is customarily desirable that can bodies of this type be also slightly 30 mouthed in at the necked in end in order to facilitate the positioning of a cover thereon and where this is desirable, the dies may be formed with a slight inward projection to bend the edge of the body inwardly as indicated by reference character 25.

After the necking in operation has been performed the body may be delivered off from the mandrel toward the right, viewing Figs. 2 and 3, by any suitable mechanism, preferably by a reciprocatory slide bar 26, carrying one or more pivoted feed dogs 27 adapted to engage the rear end of the body as shown in Fig. 3 and push it off from the mandrel. 40

The construction, operation and inherent advantages of my invention should be understood and appreciated from the foregoing without further description and it should be obvious that the variations in the mechanical details disclosed may be resorted to within wide limits without exceeding the scope of 45 the invention as defined in the following claim.

I claim:

In a can body forming machine, the combination of a horn upon which can bodies are 50 formed and along which said bodies are longitudinally fed in succession, a necking-in mandrel forming an extension of said horn and comprising a plurality of solid flat sections of different diameters disposed face to 55 face and removably secured to said horn so as to be replaceable by other sections corresponding to the sizes of different bodies to be necked, and external dies adapted to 60 compress a can body around said mandrel to effect 65 the necking in operation.

In witness of the foregoing I affix my signature.

WILLIAM CAMERON.
